UNITED STATES PATENT OFFICE.

FRANCIS H. DOANE, OF NEWTON, MASSACHUSETTS, ASSIGNOR TO THE
FRANK RIDLON COMPANY, OF SACO, MAINE.

ELECTRIC RHEOSTAT.

SPECIFICATION forming part of Letters Patent No. 558,362, dated April 14, 1896.

Application filed September 30, 1895. Serial No. 564,074. (No model.)

To all whom it may concern:

Be it known that I, FRANCIS H. DOANE, a citizen of the United States, residing at Newton, in the county of Middlesex and State of Massachusetts, have invented certain new and useful Improvements in Rheostats, of which the following is a specification.

My invention relates to rheostats; and it consists, essentially, in a rheostat having its resistances composed of one or more bars of highly-resisting material arranged and connected as hereinafter more fully described.

My invention is especially adapted for use as a starting-rheostat—that is to say, one which is used for the purpose of starting electric motors by gradually reducing the resistance of the circuit until a desired maximum current through the motor is obtained. I have consequently shown and described a preferred form of my invention as embodied in a starting-rheostat, but I do not consider that the advantages of my device are limited to such a use.

In the accompanying drawings, Figure 1 represents a top plan view of a rheostat embodying my invention. Fig. 2 is an edge view of the same. Fig. 3 is a plan view thereof with the cover removed. Fig. 4 is a central transverse section taken on the line *x x* of Fig. 1. Fig. 5 is a detail view of a part hereinafter described. Fig. 6 is a diagrammatic view showing the electrical connections of the apparatus.

In making my rheostat I prefer to provide a shallow box A, such as shown in the drawings, which may have suitable lugs *a* whereby it may be secured to any desired support. Within this box I place the resistances which in use are to be introduced into or withdrawn from the circuit. Such resistances have hitherto usually been made of wire, and the main objections to such a material which have arisen are, that, inasmuch as the metal of which the wires are composed is a good conductor of electricity, such wires generally have to be made of great length in order to provide the desired resistance, and are expensive on that account, and they also, by reason of their length, ordinarily make a rheostat heavier and more cumbrous than is desirable. In my invention I have obviated

these difficulties by using graphite for the resistances, which material I have found to be especially useful for this purpose for the reason that it has a much greater resistance than any metal, and consequently but little of it need be used to produce a high resistance, while it also possesses the advantages of cheapness and compactness, and does not burn out nor deteriorate, even when heated to a red heat.

I prefer to make my graphite resistances in the form of short bars 2. I have shown a number of these bars held in place in the box A by means of a metallic strip 3, provided with holding-clips 4, which are clamped around the centers of the graphite bars and thereby firmly hold the same in position, as shown in Fig. 3. The strip 3 is fastened to the bottom of the box and is insulated therefrom. A convenient way of making electrical connections with the graphite bars 2 is by means of metallic clips 5 clamped around the same, to which suitable connecting-wires 6 are attached. I have shown four of these clips 5 on each bar 2 of graphite. By this means I get four different resistances from each bar, as will presently be explained more fully.

The mechanism for introducing the various resistances is preferably located on the outside of the cover B of the box A. This cover should be made of some suitable insulating material—such, for instance, as slate—and apertures 7 should be left in the ends of the box B for the sake of ventilation. On the top of the cover B, I provide a number of metallic contacts 8, which are arranged in two rows, as shown, the individual contacts being "staggered" to those opposite, so that they will be successively engaged on alternate sides by the slider 9. Each contact-piece may consist of a block 9, secured in any suitable manner to the slate top B and provided with a metallic spring-arm 10, which bears against the top of the slide 9 when the latter is moved thereunder, and between which and the graphite bars electrical connection is made, as will presently be described. These contact-pieces 8 are insulated from each other by the air-space which exists between them, or, if desired, positive insulating material, such as mica, may be

placed between them. The slider 9 is guided and at the same time held against the top B of the box on which it slides by means of the guides 11, which lap over its beveled edges. 5 It is provided with an insulated handle 12, whereby it may be moved under the successive contact-pieces 8, thus making electrical connection therewith, until at the limit of its forward movement its front end 13, which is 10 flattened, as shown, engages the metallic contacts 14 and 14^a. The slider 9 is preferably provided at its rear end with a rod 15, which passes through and is guided in a bearing 16. This rod has a head 17 at its outer end, between which head and the bearing 16 a coiled spring 15^a is arranged, which tends to keep the slider 9 in the position shown in Figs. 1 and 2 of the drawings.

My preferred method of connecting the various resistances and electrical contacts of my rheostat is shown in Fig. 6, in which the contact-pieces 8, the graphite bars, and the connecting-wires are shown diagrammatically, it being understood, of course, that 20 the graphite bars are in reality located beneath the contact-pieces 8, and that the connecting-wires pass through the cover of the box. The first contact-piece which is engaged by the slider 9 is connected to the clip 25 5 on one extreme end of one of the graphite bars (which one is immaterial) by a wire 20. The second contact-piece to be engaged is connected to one extreme end of another bar, or, preferably, to the other extreme end of 30 the same bar by a wire 21. The third contact-piece is connected to an extreme end of another graphite bar by a wire 22, and so on until all the extreme ends of the graphite bars have been connected, as shown. The 35 next connection is made by means of a wire 23 from the next contact-piece to one of the intermediate clips 5. The next contact-piece is connected to another intermediate clip, and so on. It will be seen that for each clip 5 40 there is a corresponding contact-piece 8, electrically connected therewith.

The number of graphite bars and the number of clips 5 on each bar can of course be varied from the specific arrangement shown 45 in the drawings; but in making the connections between the clips and the contact-pieces 8 the same order must be observed as above described—namely, the clips on the extreme ends of the graphite bars are to be connected to the contact-pieces which are the first to be 50 engaged by the slider 9, the next adjacent clips to the next group of contact-pieces to be engaged, and so on, the clips nearest the holding-strip 3 being connected to the last group 55 of contact-pieces. The reason for this arrangement will be apparent when the operation 60 of the device is described.

Two binding-posts 18 and 19 are provided on the cover B, which in use are connected in 65 the circuit with the motor and the source of energy. It is immaterial at which post the current enters the rheostat.

The metallic strip 3 which holds the graphite bars is electrically connected by a wire 24 to one of the binding-posts, as 18, and the same 70 binding-post is also electrically connected to the metallic contact-piece 14. The other binding-post 19 is connected to the slider 9 by means of a wire 25, attached to the bearing 16, and it is also electrically connected to the 75 contact-piece 14^a by a wire 26.

As thus constructed, the operation of my device is as follows: When the slider 9 is thrown back by the spring 15^a to its normal position, no current can pass through the device. When it is moved forward until it engages with the nearest contact-piece 8, an electrical connection is established between the binding-posts 18 and 19 by means of the wires 24 25 20, the slider 9, the metallic strip 85 3, and the graphite bar 2, to which the wire 20 is connected, and the resistance thus introduced into the circuit depends upon the half-length and the diameter of the graphite bar, the resistance of the wires and other 90 parts being negligible in comparison therewith. This represents the greatest resistance which can be thrown into the circuit by means of the rheostat, and consequently under such circumstances a minimum current will flow 95 from one binding-post to the other, the dimensions of the graphite bar being of course calculated, so as to produce the desired minimum current. When the slider is pushed forward until it engages the second contact-piece 8, an additional path for the current is offered through the wire 21 and its graphite bar, and the resistance through this path being equal to the former resistance and the two being joined in multiple are, the total 100 resistance is thereby halved, and consequently twice the current will flow. In the same manner, as the slider is pushed forward, successive half-lengths of graphite are thrown into the circuit in multiple are and the resistance 105 is thereby successively reduced in corresponding proportion. When the slider has passed half-way down, it reaches the contact-piece to which the wire 23 is attached, and as said wire is connected to its graphite bar 2 at an 110 intermediate point of its length, the resistance is diminished in proportion to the length of the graphite thus cut out and a further increase of current takes place, and so on, the intermediate clips 5 being successively 115 thrown into the circuit in multiple are until the slider is in electrical contact with all the contact-pieces 8. Its end 13 may then finally be pushed under the contact-pieces 14 and 14^a, and as these are connected respectively 120 with the binding-posts 18 and 19 the entire current is allowed to short-circuit through the slider without passing through any of the graphite resistances. The motor being 125 thus started and supplied with the full current it is desirable that the slider be held with its end 13 in contact with the pieces 14 and 14^a. To this end I have provided a spring-arm 130 b, secured to the cover B and adapted to

engage with a notch *c* in the rod 15 when the slider is moved forward to its short-circuiting position, where it is thus held until released by pressing the spring-arm *b* upward, when it is thrown entirely out of contact with any of the contact-pieces by means of the spring 15^a. The advantage of having this spring 15^a is that it is thereby rendered impossible for the current to be accidentally left partially turned on.

While I have described my device as a starting-rheostat, yet it is equally well adapted for use wherever it is desired to introduce a varying resistance into an electrical circuit, and it may obviously be changed in many respects to adapt it to such uses without departing from the spirit of my invention.

I have also described graphite as being my preferred material for the resistances, but 20 bars of other highly-resisting materials, such as are well known in the art, may of course be used instead, and the number of such bars may be varied as desired, and also the number of metallic clips 5 on each bar. Furthermore, I do not consider myself limited to the 25 precise arrangement shown and described of the terminal connections of the resistances.

I claim—

1. In a rheostat the combination of a plurality of bars of highly-resisting material, metallic bands secured to the same at suitable intervals of their lengths, a contact-terminal corresponding to each metallic band, said bands being electrically connected each

to a contact-terminal, and the said bars being also connected through a common metallic strip to the external circuit, and a movable arm completing the connection with the external circuit and arranged to make contact with the said contact-terminals successively, 35 all substantially as described.

2. In a rheostat, the combination of a metallic holding - strip electrically connected with the external circuit, a plurality of graphite bars held by said strip, one or more electrical connections from each of said bars to suitable contact-terminals, and a movable arm arranged to make contact with the said terminals successively, said arm being also connected with the external circuit, all 45 50 substantially as described.

3. In a rheostat, in combination with a plurality of contact-terminals and means for throwing the same into circuit successively, a bar of resisting material electrically connected to the external circuit and provided with a plurality of metallic connections for the purpose set forth, each of the said connections being electrically connected to one of the said contact-terminals, all substantially 55 60 as described.

In testimony whereof I have hereunto subscribed my name this 24th day of September, 1895.

FRANCIS H. DOANE.
